Application July 12, 1947, Serial No. 760,630

6 Claims. (Cl. 315—100)

1

This invention relates to a current control circuit and, more particularly, to an improved current control starting circuit for firing a fluorescent lamp.

A fluorescent lamp in general comprises a suitable mixture of inert gases contained within an elongated tubular envelope having its interior surface coated with a fluorescent substance. Widely spaced thermionic electrodes of filamentary form are mounted within the tubular envelope near opposite ends thereof. In lighting the lamp, it is first necessary to ionize the gaseous atmosphere within the envelope by heating the filamentary electrodes to an electron emitting temperature because at room temperatures the gas will not pass sufficient current for ordinary lighting purposes. This is accomplished by employing a current control starting circuit which permits the flow of a relatively high current through the filamentary electrodes in series to preheat them to the point of electron emission.

When the temperature of the electrodes reaches this point, the current control circuit abruptly interrupts the flow of current thereby causing a relatively high firing potential to be momentarily applied to the electrodes. This ionizes the gaseous atmosphere within the envelope which then serves as a conductive medium for sustaining a current flow between the electrodes at line potential. This line current flow through the gaseous atmosphere between the electrodes generates high intensity radiations within the invisible portion of the spectrum which, as is well known in the art, excite the fluorescent coating on the interior of the lamp and cause it to fluoresce thereby producing visible light.

In designing a current control circuit for controlling the application of the preheating current and the firing potential, it is necessary that the circuit be designed to allow ample time for preheating the electrodes before causing the firing potential to be applied as otherwise the electrodes would be damaged, the ends of the lamp would be darkened, and considerable flickering and sputtering of the lamp would occur. On the other hand, it is also desirable, for obvious reasons, that a starting circuit should be designed to consume no more time in the preheating period than is necessary to raise the temperature of the electrodes to an adequate emissive temperature. In attempting to strike a balance between insufficient preheating and unduly long preheating, it sometimes happens that a starting circuit will fail to fire the lamp.

Accordingly, it is an object of this invention to provide an improved current control circuit.

It is also an object of this invention to provide an improved current control circuit for controlling the application of a firing potential to a fluorescent lamp.

2

Another object of the invention is to provide an improved current control starting circuit for firing a fluorescent lamp smoothly and without flickering or sputtering.

5 Still another object is to provide an improved current control circuit for effecting the preheating of the filamentary electrodes of a fluorescent lamp the instant that the line voltage is applied to the lighting circuit of the lamp.

10 A further object is to provide an improved current control starting circuit for effecting adequate preheating of the filamentary electrodes of a fluorescent lamp and for causing a firing potential to be applied to them.

15 An additional object is to provide an improved current control starting circuit for causing a firing potential to be automatically and repeatedly applied to the filamentary electrodes of a fluorescent lamp and for automatically deactivating itself in the event the lamp fails to fire after a preassigned interval of time.

20 These and other objects of the invention are attained by means of an improved current control circuit having a heating element constituted by a high resistance which is connected in series with an inductive ballast and the lamp electrodes. This high resistance is normally virtually short-circuited by a shunt path which includes a resistance wire heating element. The resistance

25 wire heating element is helically wound around the high resistance and both of them are disposed in heating relationship to a normally closed bimetallic switch. As soon as the line current is applied to the lighting circuit of the lamp, the 30 current will immediately flow through the shunt path in the starting circuit and will thereby immediately start to preheat the filamentary electrodes.

35 During this time, the resistance wire heating element becomes hot and radiates heat to both the high resistance and the bimetallic switch. The bimetallic switch and the resistance wire heating element are so proportioned that the switch will open at about the same time that the 40 electrodes become sufficiently preheated for a discharge to be initiated across the lamp. When the shunt path across the preheated high resistance is thus opened, a high voltage surge is produced across the electrodes by the inductive ballast and the lamp should fire.

45 If, for various reasons, the lamp fails to fire, the line current now applied to the preheated high resistance will cause it to generate more heat which is radiated to the bimetallic switch causing it to open still further until it engages a second bimetallic switch which also has a resistance wire heating element connected to it in heating relationship. This establishes another virtual short-circuit across the high resistance. 50 Current will now flow through this second shunt

path to continue the preheating of the electrodes. During this time, the second resistance wire heating element will become hot and will radiate heat to the second bimetallic switch. Also during this time, the high resistance becomes cool.

Thus, the heating of the second resistance wire heating element tends to disengage the second bimetallic switch from the first bimetallic switch by moving the former in one direction while, at the same time, the cooling of the high resistance is conducive to disengagement of the two switches by permitting the first bimetallic switch to move in the opposite direction. The combination of these two opposite actions causes the two bimetallic switches to separate quickly opening the second shunt path across the high resistance. This causes the inductive ballast to produce a second high voltage surge across the electrodes which should fire the lamp.

If the lamp still fails to fire, the two bimetallic switches will again move into engagement with each other and the sequence of operations described in the preceding paragraph will be repeated until the ambient temperature within the housing structure of the starting circuit rises to a sufficiently high degree to hold the bimetallic switches in their extreme positions, as is described in more detail hereinafter, thereby preventing further recycling operations.

These and other features of the invention are more fully discussed in connection with the following detailed description of the drawing in which:

Fig. 1 is a schematic circuit diagram of the improved current control circuit, and

Fig. 2 is a front perspective view with the housing structure broken away to show the compact manner in which the components of the improved current control starting circuit are assembled.

In Fig. 1, a fluorescent lamp 1 containing a suitable mixture of inert gases is shown to be provided with oppositely disposed filamentary electrodes 2 and 3 near each end thereof. A supply source of the customary domestic potential, such as a power line supplying 115 volt 60 cycle current, is indicated by the reference numeral 4 for operating the lamp 1. One side of the power supply source 4 is connected through a suitable ballast impedance, such as a choke coil 5, to the electrode 3. The other side of the power source 4 is connectable through a manually operable control switch 6 to the electrode 2. The electrodes 2 and 3 are connected in series through a suitable high resistance 7 which also functions as a heating element in the current control circuit as is described hereinafter.

A current control starting circuit 8 for controlling the application of both the preheating current and the firing potential to the electrodes 2 and 3 is connected across the high resistance 7 in shunt relation thereto. This current control circuit 8 includes a resistance wire heating element 9 which is helically wound around the high resistance 7, as is shown in Fig. 2, for efficiently radiating heat thereto. As can further be seen in Fig. 2, both the high resistance 7 and the resistance wire heating element 9 are disposed in heating relationship to a flexible bimetallic switch 10 composed of any two suitable metals having dissimilar thermal expansion coefficients. One end of the bimetallic switch 10 is fixedly mounted at the point 11. Near the other end of the bimetallic switch 10, a metallic contact rod 14 is affixed to one side thereof by any convenient means, such as by welding. The end of the contact rod 14

is bent at an angle for movement against a stop provided by a mounting card indicated schematically at 24.

Another flexible bimetallic switch 16 composed of any two suitable metals having dissimilar thermal expansion coefficients has one end fixedly mounted at the point 17 in electrically conductive engagement with one end of the resistance wire heating element 9. A second metallic contact rod 18 is affixed, as by welding, to the bimetallic switch 16 near its other end for engagement with the first contact rod 14.

When the starting circuit 8 is in an unenergized condition, as is shown in Fig. 1, the contact rods 14 and 18 are in engagement with each other. Since the resistance wire heating element 9 has a much smaller resistivity than that of the high resistance 7, the engagement of the contact rods 14 and 18 virtually short-circuits the high resistance 7. The free end of the bimetallic switch 16 is bent at an angle for movement against a stop provided by another portion of the same mounting card 24. This bimetallic switch 16 is heated only by the ambient temperature of the air inside the housing structure which completely encloses the starting circuit 8 as is shown in Fig. 2.

Still another flexible bimetallic switch 19 composed of any two suitable metals having dissimilar thermal expansion coefficients has one end fixedly mounted at the point 20. The other end of the switch 19 is bent upward at an angle to form a contact lip 21 for engagement with the contact rod 14. When the starting circuit 8 is in an unenergized condition, as is shown in Fig. 1, the contact lip 21 does not engage the contact rod 14. A second resistance wire heating element 22 is disposed in heating relationship to the bimetallic switch 19 and has one end connected in electrically conductive engagement with the switch 19 at the point 20.

To operate this current control circuit, the manually operable control switch 6 is first closed to apply the line current from the source 4 to the inductive ballast 5 in series with the electrodes 2 and 3 and the resistance wire heating element 9 in the shunt path across the high resistance 7. This flow of current through the electrodes 2 and 3 causes them to become warm thereby partially ionizing the gaseous atmosphere contained within the envelope of the lamp 1. At the same time, the flow of current through the resistance wire heating element 9 causes it to become hot.

The heat thus generated by the resistance wire heating element 9 is radiated to the bimetallic switch 10 and also to the high resistance 7 which both become warm due to their proximity which is more evident in Fig. 2. The bimetallic switch 10 finally becomes so hot that it bends downward thereby opening the circuit through the contact rods 14 and 18. As was stated above, the resistance wire heating element 9 and the bimetallic switch 10 are so proportioned that the contact rods 14 and 18 will separate at about the same time that the electrodes 2 and 3 become sufficiently preheated for a discharge to be initiated across the lamp 1.

The sudden opening of the circuit through the contact rods 14 and 18 opens the shunt path across the high resistance 7 thereby, in effect, switching it in series with the inductive ballast 5 and the electrodes 2 and 3. This resistance 7 has such a high resistivity that the sudden switching of it into the circuit has almost the same effect as opening the series circuit through

the inductive ballast 5 and the electrodes 2 and 3. This interruption causes the inductive ballast 5 to produce a high voltage surge or "kick" across the preheated electrodes 2 and 3 thereby completing the ionization of the gaseous atmosphere contained within the envelope of the lamp 1 and resulting in the striking of a low voltage arc which, when once started, will be sustained by the line voltage with the electrodes 2 and 3 being maintained at a discharge sustaining temperature by the discharge current through the lamp 1. A small condenser 23 is connected across the high resistance 7 to minimize sparking or arcing when the contact rod 14 moves away from the contact rod 18 to open the shunt path across the high resistance 7.

During the time that the lamp 1 remains in operation, a small amount of current will flow through the preheated high resistance 7 to maintain it warm. The heat now generated by the high resistance 7 is radiated to the bimetallic switch 10 and keeps it sufficiently warm to maintain the contact rod 14 in an open position approximately midway between the contact rod 18 and the contact lip 21 but not sufficiently downward to engage the mounting card 24. The above-mentioned shunt path in the starting circuit 8 thus remains open as long as the lamp 1 is in operation.

It should be noted that, because of its relatively large mass, the heat inertia of the high resistance 7 is great. However, this inertia is overcome during the initial attempt to fire the lamp 1 due to the high resistance 7 having been first preheated by heat radiated by the resistance wire heating element 9.

In the event that the lamp 1 should fail to fire, a larger amount of current will flow through the high resistance 7. This current will have a voltage about double that which it would have had if the lamp 1 had fired. The resistance 7 will therefore become hotter than it would have been under the conditions described in the preceding paragraph and, due to its proximity as shown in Fig. 2, will radiate a relatively high amount of heat to the bimetallic switch 10. The bimetallic switch 10 now becomes so hot that it bends further downward until its contact rod 14 engages the contact lip 21 to close an auxiliary shunt path across the high resistance 7.

Since the resistance wire heating element 22 in this shunt path has a considerably smaller resistivity than the high resistance 7, most of the line current will now flow through this path instead of through the high resistance 7 which will now become cooler and will cease to radiate as much heat to the bimetallic switch 10 so that it also will become cooler.

This flow of current through the resistance wire heating element 22 causes it to produce heat which is radiated to the bimetallic switch 10 due to their proximity as shown in Fig. 2. This heat tends to cause the bimetallic switch 10 to bend downward. During this time, the cooling of the high resistance 7 tends to permit the bimetallic switch 10 to cool as was described in the preceding paragraph so that it begins to bend upward. Due to these simultaneously opposite actions, this auxiliary shunt path is quickly opened to again place the high resistance 7 in series with the filaments 2 and 3. As was stated above, this in effect interrupts the series circuit through the inductive ballast 5 and the electrodes 2 and 3 due to the high value of resistance 7. The high voltage surge now pro-

duced by the ballast coil 5 due to this interruption is applied to the preheated electrodes 2 and 3 in another attempt to fire the lamp 1.

This sequence of operations is quickly repeated several times if necessary. If the lamp 1 fails to fire during these operations, the ambient temperature of the air inside the housing structure, which completely encloses the starting circuit 8 as is shown in Fig. 2, finally rises to a point 10 sufficiently high to cause all three bimetallic switches 16, 10, and 19 to bend further downward. The bimetallic switch 19 is free to bend far downward so that its contact lip 21 will be out of engagement with the contact rod 14. The downward bend of the bimetallic switch 10 is arrested due to the bent end of its contact rod 14 hitting against the stop constituted by the mounting card 24. Similarly, the downward bend of the bimetallic switch 16 is arrested due to its bent end striking against the stop constituted by the mounting card 24. Since the distance between the mounting card 24 and the tip of the bimetallic switch 16 is shorter than the distance between the mounting card 24 and the tip of the contact rod 14, the contact rod 14 will now bend down further than the bimetallic switch 16. This prevents the contact rod 18 from coming into engagement with the contact rod 14 at this time.

30 Thus, both the main shunt path across the high resistance 7 and the auxiliary shunt path across the high resistance 7 will now be held open due to the heat inside the housing structure holding the three bimetallic switches 16, 10, and 19 in the downward positions just described. The starting circuit 8 will remain in this condition due to the heat produced by the flow of line current through the high resistance 7. With both the shunt paths being thus held open, no further attempt to fire the lamp 1 will be made until the control switch 6 has been opened to discontinue the flow of current through the high resistance 7 and until the ambient temperature within the housing structure becomes sufficiently 45 reduced to permit the bimetallic switches 16, 10, and 19 to move up out of their extreme downward positions.

It is to be noted that the reason for the stops provided by the bent ends of the contact rod 14 and the bimetallic switch 16 hitting against the mounting card 24 is not only to prevent the contact rod 18 from engaging the contact rod 14 at this time but also to prevent the contact rod 14 from being carried down far enough to engage 55 the contact lip 21 during this period of high ambient temperature.

In Fig. 2, the current control starting circuit 8 of Fig. 1 is shown to be mounted on a card 24 of insulating material and is also attached to a base 25 of insulating material. The base 25 together with a cylindrical casing 26 of any suitable material constitute a housing structure which completely encloses the starting circuit 8. The base 25 is provided with terminals 27 and 60 28 for facilitating the electrical connection of the starting circuit 8 to the lighting circuit of the lamp 1 of Fig. 1. It can be seen in Fig. 2 that the high resistance 7 is connected across the terminals 27 and 28 and that the condenser 23 is also connected across the terminals 27 and 28 in shunt with the resistance 7.

65 The bimetallic switch 10 is shown to be bent in the form of a J and is attached to the mounting card 24 at the point 11 by any suitable means, such as by a rivet. It is electrically connected to

the terminal 28 by a conductor 29 which passes through an eyelet 30, along the back of the mounting card 24, and then through another eyelet 33. The free end of the bimetallic switch 10 has welded thereto one end of a metallic contact rod 14 which has its other end bent at an angle for serving as a stop arm for the purpose discussed above in the description of Fig. 1.

The contact rod 14 is normally in contact with another metallic contact rod 18 welded near one end of the bimetallic switch 16. The bimetallic switch 16 is also bent in the form of a J and is attached to the mounting card 24 at the point 17 in a manner similar to that of the bimetallic switch 10. The other end of the bimetallic switch 16 is bent at an angle to serve as a stop arm for the reason described above. The fixed end of the bimetallic switch 16 has soldered thereto one end of the resistance wire heating element 9 which is helically wound around the Bakelite shell of the high resistance 7 in order to efficiently radiate heat thereto. The other end of the resistance wire heating element 9 is soldered to the conductor 31 which is connected to the terminal 27.

It is to be noted that both the high resistance 7 and the resistance wire heating element 9 pass through the bend at the bottom of the bimetallic switch 16 in order that the heat which they generate may be more efficiently radiated to the bimetallic switch 10. It is especially to be noted that, due to the resistance wire heating element 9 being superimposed upon and wound around the high resistance 7, the heat generated by the resistance wire heating element 9 will be efficiently radiated to the high resistance 7 for pre-heating it as was discussed above in the description of Fig. 1.

The bimetallic switch 19 has one end bent in the form of a J which is affixed to the mounting card 24 at the point 20 in a manner similar to that of the bimetallic switch 10. The other end of the bimetallic switch 19 is bent upward to form a contact lip 21 for engagement with the contact rod 14. If desired, instead of thus bending the end of the bimetallic switch 19, a short section of contact rod material may be soldered along the top edge of the bimetallic switch 19 for performing the same function as the contact lip 21. The bimetallic switch 19 is heated by the resistance wire heating element 22 which has one end soldered to the lead-in conductor 31 and has its other end soldered to the fixed end of the bimetallic switch 19.

In order that the heat generated by the resistance wire heating element 22 will not be effectively radiated to the other bimetallic switches 10 and 16, the wire 22 is passed from the back of the card 24 through an eyelet 32, then along the front of the card 24, through another eyelet 33, along the back of the card 24, and then through another eyelet 34 to the fixed end of the bimetallic switch 19.

The eyelets 32, 33, and 34 also perform a spacing function by reason of their rims projecting slightly out from the mounting card 24 and thereby serving to space the wire 22 a short distance away from the mounting card 24 so that it will not become burnt or charred when the wire 22 becomes hot. In addition, these eyelets 32, 33, and 34 also function to absorb some of the excess heat produced by the resistance wire heating element 22.

The J-bend at the fixed end of the bimetallic switch 16 is large enough to provide sufficient

spacing between the free end of the bimetallic switch 16 and the resistance wire heating element 22 so that it will not be effectively heated thereby. In this regard, it should be noted, as was stated above in the description of Fig. 1, that the bimetallic switch 16 is heated only by the ambient temperature within the housing structure constituted by the casing 26 and the base 25.

It is to be noted that the bimetallic switches 10, 16, and 19 are self-compensating for normal changes in the ambient temperature within the housing structure or for changes in room temperature. This is because such temperature changes will effect equal movement of the free ends of each of the bimetallic switches 10, 16, and 19 so that their relative positions with respect to each other will remain the same.

It is to be understood that the specific construction described above and shown in the drawing is for the purpose of explaining the nature of this invention and that various modifications may be made therein without departing from the scope of the invention which is to be limited only by the claims appended hereto.

What is claimed is:

1. In combination, a source of electric current, a high resistance, a normally closed main shunt circuit connected across said high resistance, a normally open auxiliary shunt circuit connected across said high resistance, and means for applying current from said source to said high resistance and said main and auxiliary shunt circuits, said main shunt circuit having a normally closed first bimetallic switch connected in series with a first resistance wire heating element helically wound around said high resistance for efficiently radiating heat thereto and disposed in heating relationship to said first bimetallic switch, and said auxiliary shunt circuit including a normally open second bimetallic switch and expediting means for expediting movement of said second bimetallic switch, said expediting means comprising a second resistance wire heating element connected in series in said auxiliary shunt circuit and disposed in heating relationship to said second bimetallic switch for radiating heat thereto.

2. In combination, a source of electric current, a fluorescent lamp having filamentary electrodes, a normally open control switch, an inductive ballast, a high resistance having one end connected to one of said electrodes and having another end connected to another of said electrodes, circuit means for connecting said control switch and said inductive ballast and said high resistance and said electrodes all in series with said source of current, a normally closed main shunt circuit connected across said high resistance, said main shunt circuit including first and second contact means normally in engagement with each other and connected in series with a first resistance wire heating element adapted to generate and radiate heat upon the closure of said control switch, said second contact means including first bimetallic means, said first resistance wire heating element being disposed in heating relationship to said first bimetallic means for radiating heat thereto, said first bimetallic means being adapted when hot to move said second contact means out of engagement with said first contact means for opening said normally closed main shunt circuit, said inductive ballast being adapted to produce a first high voltage surge between said electrodes upon the opening of said main

shunt circuit across said high resistance, said high resistance being adapted to become hot and to radiate heat upon the opening of said main shunt circuit with said control switch closed, said high resistance being disposed in heating relationship to said first bimetallic means for radiating heat thereto, and a normally open auxiliary shunt circuit connected across said high resistance and including third contact means having second bimetallic means connected in series with a second resistance wire heating element disposed in heating relationship to said second bimetallic means for radiating heat thereto, said first bimetallic means being adapted when heated by said high resistance to move said second contact means into engagement with said third contact means for closing said auxiliary shunt circuit across said high resistance, said second resistance wire heating element being adapted to become hot upon the closure of said auxiliary shunt circuit for heating said second bimetallic means, said first bimetallic means being adapted to move said second contact means out of engagement with said third contact means after said auxiliary shunt circuit is closed, said second bimetallic means being adapted when hot to move said third contact means out of engagement with said second contact means for opening said auxiliary shunt circuit, and said inductive ballast being adapted to produce a second high voltage surge between said electrodes upon the opening of said auxiliary shunt circuit across said high resistance.

3. A combination in accordance with claim 9 and comprising in addition a housing structure for completely enclosing said high resistance and both said main and auxiliary shunt circuits, said first contact means including third bimetallic means, and a stop member disposed within said housing structure, all of said three bimetallic means being adapted to move their associated contact means toward said stop member upon an increase in the ambient temperature within said housing structure, said second contact means having a first stop instrumentality adapted to hit against said stop member for holding said second contact means out of engagement with said third contact means, and said first contact means having a second stop instrumentality adapted to hit against said stop member for holding said first contact means out of engagement with said second contact means whereby both said main and auxiliary shunt circuits are held open.

4. A current control starting circuit for an electric gaseous discharge device having a plurality of filamentary electrodes, said starting circuit comprising in combination a high resistance having one end connected to one of said electrodes and having another end connected to another of said electrodes, circuit means including a main shunt path and an auxiliary shunt path for shunting said high resistance, switching means having at least three switch arms for controlling said shunt paths, the first and second of said switch arms being normally in electrically conductive engagement for closing the main shunt path, the third of said switch arms being normally out of electrically conductive engagement with the other two switch arms for opening the auxiliary shunt path, means for causing said high resistance to become hot and to radiate heat to the second switch arm, said second switch arm, being adapted when hot to move into electrically conductive engagement with

the third switch arm for closing the auxiliary shunt circuit, said high resistance being adapted to cool and to cease radiating heat to the second switch arm when said auxiliary shunt circuit is closed, said second switch arm being adapted to move away from the third switch arm for opening the auxiliary shunt circuit when heat ceases to be radiated to it by the high resistance, and accelerating means for accelerating the opening of the auxiliary shunt circuit after it has been closed, said accelerating means comprising a resistance wire heating element connected in series with the third switch arm and disposed in heating relationship thereto and adapted to become hot when said auxiliary shunt circuit is closed, said third switch arm being adapted to move away from the second switch arm for opening the auxiliary shunt circuit when heat is radiated to it by said resistance wire heating element.

5. In a current control starting circuit for firing an electric gaseous discharge device having a plurality of filamentary electrodes with means for producing a first high voltage surge between said electrodes for firing said device, circuit means for quickly producing a second high voltage surge between said electrodes in the event said device fails to fire in response to the first high voltage surge, said circuit means including two switch arms of bimetallic material, the first of said switch arms being adapted when hot to move into electrically conductive engagement with the second of said switch arms and when cool to move out of engagement therewith, the second of said switch arms being adapted when hot to move out of electrically conductive engagement with said first switch arm, and heat radiating means adapted to radiate heat to said second switch arm only after said first switch arm has been heated and is beginning to cool.

6. A current control starting circuit for an electric gaseous discharge device having a plurality of filamentary electrodes, said starting circuit comprising in combination a high resistance having its first end connected to a first one of said electrodes and having its second end connected to a second one of said electrodes, a first bimetallic switch arm, a first resistance wire heating element having one end connected to said first switch arm and having its other end connected between the second end of the high resistance and said second electrode, a second bimetallic switch arm, a second resistance wire heating element having one end connected to said second switch arm and having its other end connected between the second end of the high resistance and said second electrode, a third bimetallic switch arm having a fixed end and a free end adapted to move into electrically conductive engagement with said first and second switch arms alternatively, and circuit means for connecting the fixed end of said third switch arm between the first end of the high resistance and said first electrode.
